J. BETHENOD

HIGH FREQUENCY SIGNALING SYSTEM

Filed May 6, 1922

Inventor

JOSEPH BETHENOD

By his Attorney *Ira J. Adams*

UNITED STATES PATENT OFFICE.

JOSEPH BETHENOD, OF PARIS, FRANCE.

HIGH-FREQUENCY SIGNALING SYSTEM.

Application filed May 6, 1922. Serial No. 559,009.

To all whom it may concern:

Be it known that I, JOSEPH BETHENOD, a citizen of the Republic of France, and a resident of Paris, France, have invented certain new and useful Improvements in High-Frequency Signaling Systems, of which the following is a specification, accompanied by drawings.

The object of the present invention is to provide arrangements for increasing and regulating the synchronizing connection of high frequency alternators connected in parallel.

The new circuit arrangement to be hereinafter described has two important advantages:

1. The condensers are only traversed by the synchronizing current, whereby their work is materially reduced.
2. The adjustment of the synchronizing connection may be effected independently of the adjustment of the useful individual load of the alternators. As a result of this, the adjustment is easily accomplished because it becomes independent of the usual placing in resonance of the charging circuit comprising the connected alternators and the external apparatus (antennæ, etc.)

In the single figure of the drawing a circuit arrangement is shown in accordance with the above. The high frequency alternators 1 and 2 are assumed directly to feed the antenna 3. One of the poles of each of the alternators is connected to the ground 4 and the two alternators are interconnected through the agency of an inductance coil 5, the central point of which is connected with the antenna 3. The terminals of this coil are short-circuited through the coupling condenser 6, the latter being preferably connected in series with a tuning coil 7.

It will be therefore readily seen that the condenser is traversed only by the synchronizing current, and this current may be tuned to the most suitable value by means of the coil 7. On the other hand, if the magnetic leakage between the two sections of the coil 5 is materially reduced, the ensemble comprising 5 and 6 has practically no appreciable influence on the tuning of the useful current supplied to the antenna 3, the ampere turns corresponding to this current being practically zero. However, the coil 5 may be replaced by a system of two inductances or two capacities connected in series, the

junction point being in turn connected to the antenna 3. But in this case, the system has a certain function in the tuning of the useful output current. However, the tuning of the synchronizing current may be independently effected by means of the ensemble, 60 6, 7.

Obviously, the above described circuit arrangements may be variously modified and more particularly, may be adapted for systems in which the alternator is not connected directly to the antenna as shown in the system herein described, but through a transformer. The arrangement may also be applied to systems in which a plurality of alternators are used.

Having described my invention, what I claim is:

1. The combination of a radiating unit, a plurality of parallel high frequency generators for supplying said radiating unit and a synchronizing connection between said generators comprising a pair of impedances in series shunted by a condenser, said radiating unit being connected to the junction 75 point of said impedances.

2. The combination of a radiating unit, a plurality of parallel high frequency generators for supplying said radiating unit and a synchronizing connection between said 85 generators comprising a pair of impedances in series shunted by a condenser, and an inductance in series, said radiating unit being connected to the junction point of said impedances.

3. The combination of a radiating unit, a plurality of parallel high frequency generators for supplying said radiating unit and a synchronizing connection between said generators comprising a pair of impedances in 95 series shunted by a condenser, and a variable inductance in series, said radiating unit being connected to the junction point of said impedances.

4. The combination of a radiating unit, a plurality of parallel high frequency generators for supplying said radiating unit and a synchronizing connection between said generators comprising an inductance shunted by a condenser, said radiating unit being connected to an intermediate point on said inductance.

5. The combination of a radiating unit, a plurality of parallel high frequency generators for supplying said radiating unit and a 110

synchronizing connection between said generators comprising an inductance shunted by a condenser between said generators, said radiating unit being connected to the middle 5 of said inductance.

6. The combination of a radiating unit, a plurality of parallel high frequency generators for supplying said radiating unit and a synchronizing connection between said generators comprising an inductance shunted by a condenser and an inductance in series 10 between said generators, said radiating unit

being connected to the middle of said inductance.

7. The combination of a radiating unit, a plurality of parallel high frequency generators for supplying said radiating unit, said generators being grounded at one terminal, and a synchronizing connection between the other terminals comprising an inductance 15 shunted by a capacity, said radiating unit being connected to a middle point of said inductance. 20

JOSEPH BETHENOD.
